UNITED STATES PATENT OFFICE.

ABRAHAM MOSSOVITZ, OF BALTIMORE, MARYLAND.

LIFE-PRESERVER.

1,359,267.

Specification of Letters Patent. Patented Nov. 16, 1920.

Application filed September 11, 1920. Serial No. 409,575.

To all whom it may concern:

Be it known that I, ABRAHAM MOSSOVITZ, a citizen of the United States, residing at Baltimore, in the State of Maryland, have 5 invented certain new and useful Improvements in Life-Preservers, of which the following is a specification.

This invention relates to improvements in life preservers and has for its object to provide an improved construction of device of 10 this character which may be readily carried by a person in a folded or compact condition when not in use and which can be readily inflated and put into condition for use.

15 The invention is illustrated in the accompanying drawing, wherein,—

Figure 1 shows the improved device inflated and ready for use.

Fig. 2 illustrates an enlarged detail of the 20 two ends of the device and the means for connecting said ends.

Fig. 3 shows a perspective detail of one end of the device, and

Fig. 4 illustrates a cross-sectional detail 25 through the inflated device as the same would appear if cut on the line 4—4 of Fig. 3.

Referring to the drawing by reference 30 characters, 5, designates a tube of a material such as rubber, which will retain air, which tube has two ends in distinction to being an endless or circular tube. A small tube 6, is connected to one end of the larger tube and said small tube has a valve device 7, which, 35 when the tube is inflated, may be closed to retain the large tube in the inflated condition.

The large rubber tube is provided with a 40 fabric strip 8 which is preferably cemented to the outer side thereof whereby to form a flap substantially from one end to the other of said tube, for a purpose that will presently be explained.

An outer inelastic covering tube 9, preferably of a fabric, entirely incloses and 45 covers the inner elastic tube, and this outer tube and the fabric strip 8, or flap, are permanently secured together, as for example by a row of stitches 10.

50 These stitches 10, are simply taken through the outer casing or tube and the strip or flap, and do not pass through the inner rubber tube because if taken through the rubber they would permit a leakage of air from the inner tube.

The outer tube or casing has two ends 60 11 and 12 in which the two ends of the inner elastic tube are confined, and I provide novel means at these ends for securing them together so as to form a circular or ring-shaped device as will now be explained. 65

One end of the outer casing or covering 9 carries a coupling sleeve 13 of flexible fabric. In the present instance this sleeve is secured near one end by stitching 14, to the end 11, of the covering tube 9 and has 70 a series of buttons 15 and buttonholes 17 adjacent its free edges whereby the same may be lapped about the two adjacent ends 11 and 12 and fastened by the buttons and buttonholes to hold it in the lapped condition. 75

I also provide the end 12 of the tube with buttons 21 whereby the sleeve may be directly connected to said end and I further provide a button 18, on one end and a loop 80 19 on the other end of the outer tube whereby said tube-ends may be fastened together.

When the two ends of the tube 9 are brought together the sleeve will be folded around said ends and the fasteners engaged 85 so that when the inner tube is inflated the device will assume the shape shown in Fig. 1.

An opening 20 is provided in the sleeve 90 so that the small filling tube 6, may be passed therethrough when the sleeve is fastened and in the attached position.

Obviously any form of fastening devices, 95 such as snap fasteners may be employed instead of the buttons and buttonholes.

Having described my invention, I claim,

1. In a life preserver, the combination 100 with an inner elastic tube having two ends, of an outer tube also with two ends and covering the inner tube, and a flexible sleeve lapping the two ends and secured about the latter.

2. In a life preserver the combination 105 with an inner elastic tube having two ends, of an outer tube having two ends, a strip attached to the inner tube and also connected to the other tube whereby to secure the two tubes together and a coupling device to unite the two ends of the tubes.

In testimony whereof I affix my signature. 110

ABRAHAM MOSSOVITZ.
